BERNARD LOEWE, OF PARIS, FRANCE.

PROCESS FOR OBTAINING THREAD FROM THE COCOONS OF THE SILKWORM.

1,202,543.

Specification of Letters Patent. Patented Oct. 24, 1916.

Application filed June 18, 1912. Serial No. 704,314.

To all whom it may concern:

Be it known that I, BERNARD LOEWE, of 50 Rue Labruyère, Paris, France, manufacturer, have invented a new and useful Improvement in Processes for Obtaining Thread from the Cocoons of the Silkworm, which improvement is fully set forth in the following specification.

Hitherto in order to obtain commercial silk thread called raw thread, cocoons of the silk worm have been heated in water in order to soften the gum, after which a certain number of threads derived from the same number of cocoons are united by juxtaposition, these threads adhering together by reason of their gum. These operations necessitate the employment of several apparatus and take a relatively long time; difficulties also arise from the fact that solutions are produced and from the fact that these manipulations are dependent on their success in a great measure on the skill of the workers.

Raw silk has hitherto only been wound upon reels contained in a box closed except at the side at which the thread passes in; the interior of the box being heated for the purpose of drying the thread. The silk thus obtained still contains all its gum which must be afterward removed by ungumming the silk after throwing or weaving.

This invention allows all the difficulties appertaining to the processes now in use to be overcome, and allows for example dry silk thread or raw or thrown silk entirely separated from its gum, and consequently ready for weaving or other use, to be quickly and efficiently obtained in a single machine.

This invention also avoids one of the great difficulties encountered in the processes in use, which consists in suitably assembling the cocoon threads, as these threads vary in size according to the position they occupy in the cocoon and only the skill of the workman can give a good result. Irregularities in the size of thread depend not upon the cocoon threads themselves but upon the larger or smaller proportion of the gum.

According to this process the thread is at once deprived of all its gum, thus allowing a regular thread to be obtained by a purely mechanical operation in which skill plays no part.

According to this invention the cocoons are treated chemically, preferably in the

cold, in any suitable vessel, so as completely to eliminate the gum which surrounds the filamentary matter of the cocoons. The reagent employed is an alkaline or alkaline earth solution, employed either in a caustic state or combined with a weak acid such for example as carbonic acid or silicic acid, etc. For example there may be employed a solution of caustic soda having a strength of 65 from 0° to 5° Baumé or more but in all cases brought to a degree of concentration such that according to the nature of the cocoon the gum only is attacked while the filamentary matter remains unattacked. Cocoons remain in this bath up to thirty minutes or more according to circumstances.

The ungumming solution may be employed alone or additions may be made which serve to moderate or to accelerate its action, 75 for example solutions containing definite amounts of soap. During this treatment the gum is entirely disintegrated and dissolved without altering the filamentary material, as the gum dissolves the cocoon becomes 80 more porous and the solution penetrates it completely without however altering its rounded form or creating any difficulty in the subsequent reeling.

This process avoids on the one hand 85 the troubles of hot spinning and on the other hand avoids the beating which occasions great waste and sometimes the loss of the whole cocoon. Moreover the ungumming processes employed after throwing or weaving are avoided. With this process a high efficiency is obtained; the filamentary material is not affected by the chemical baths but the cocoons being no longer injured by beating and being entirely liberated from their gum, the silk can be reeled off from the cocoon until the end. The only waste consists in the cases or upper layers formed of a thread of 90 irregular texture which are removed at the 95 moment of reeling.

After treatment in the chemical bath the ungummed cocoons may either be wound directly, or are preferably immersed in a second bath containing water which may be 105 slightly acidulated which has for effect to dissolve or neutralize the excess of reagent which remains absorbed in the cocoon. After immersion in the second bath the cocoons are reeled and the thread thus obtained 110 (single filament or raw thread formed by the reunion of several filaments twisted to-

gether) which dries very rapidly during its travel through the free air between the vessel and the winding members, is wound directly upon reels or bobbins or spun onto 5 reels or delivered directly to the mill; these different apparatus of known construction may be combined in any suitable manner with the machine for reeling the cocoons. In 10 a word the single filament or the raw thread obtained by reeling which has the brilliant appearance of ungummed raw silk may be afterward subjected to other known spinning operations and be delivered for this purpose to any suitable apparatus.

15 Any suitable apparatus may be employed for carrying out this process.

The accompanying diagrammatic drawing illustrates one form of apparatus.

The apparatus for winding the cocoon 20 comprises two tanks a_1 and a_2 placed side by side and separated by a space sufficient for the movement of the workers. In the tank a_1 divided for this purpose into several compartments are arranged baskets b having 25 suitably perforated walls to allow the liquid to circulate very freely; these baskets provided with covers c are carried by supports d fast with the tank a_1 . A pipe e_1 serves as the inlet for the ungumming solution which 30 passes out of the tank through the pipe e_1 after having remained in the tank a_1 until exhausted. The solution is then renewed and the old exhausted solution can be treated 35 for the recovery of the ungumming materials remaining in it and also the gummy matters which are of industrial value when suitably treated. The tank a_1 may be hermetically closed by a cover f which allows a 40 vacuum to be obtained in a_1 for the purpose of causing the solution to penetrate better into the cocoons. The cocoons, each enclosed in a sort of small ball g having perforated walls, which prevent them from becoming entangled after the removal of the 45 gum, are placed in the baskets f which are immersed in the ungumming solution contained in the tanks a_1 for the required time. When the ungumming is complete the baskets b are removed and are immersed in pure 50 or acidulated water contained in the tank a_2 . Cocks e_2 , e_1 , serve for the inlet and outlet of water. Or the cocoons inclosed in their balls g may be taken directly from the tank a_1 and placed in the tank a_2 where the excess of 55 ungumming liquid taken up by the cocoon is dissolved.

Above the tank a_2 are arranged upon suitable supports h rods i of glass for example or of other material of a color soft to the 60 eye. These rods can slide transversely upon their supports and be all arranged at the side of the apparatus in order not to incommod the workmen. When the cocoons are washed the workman opens a ball g , takes 65 out the cocoon, removes the cases and com-

mences to reel the cocoon by drawing the thread and laying it over some one of the rods i . When the thread j has been seized the workman may leave the cocoon free to swim on the surface of the water in the tank a_2 or he may replace the cocoon in the small ball g provided with a suitable opening for the passage of the silk thread, close the vessel and allow it to fall back into the tank a_2 where it remains during the reeling of the cocoon its weight insuring proper tension of the thread and preventing the cocoons from becoming injured by rolling one on the other and becoming entangled. The winder has only to take the threads ready for winding which lie upon the rods i and bring them to some suitable apparatus such as reels.

In the drawing the threads are shown directly wound (either each separately or several together with or without dies k which 85 equalize the size,) upon bobbins l in the known manner. The distance of the tank a_2 from the bobbins l should be such that the threads arrive dry at the bobbins. The reeling of the cocoons takes place until the end 90 without impediment, the threads do not break and they retain all their elasticity. The reeling is facilitated by the porous texture of the cocoon thus ungummed and completely impregnated with liquid which properly separates the fibers and maintains its 95 rounded shape.

In place of directly winding the threads, each separately or several juxtaposed, upon bobbins I may while reeling the cocoons by 100 means of any suitable arrangement double the thread uniting together a certain number of more or less stretched threads derived from the like number of cocoons so as to obtain a strong and homogeneous raw 105 thread ready to be woven for example. This doubling of the threads may also take place subsequently and after winding the threads upon the bobbins as previously described. Above the rods i may be arranged pegs m 110 of porcelain, glass, metal, etc., screwed upon a rod n between which pegs the threads are passed so as to insure perfect tension before passing to the bobbins l . There may be combined with this apparatus any known appliances for winding cocoons or throwing silk such as bobbins, etc. by means of which I can obtain with a single machine and in a relatively short time from the crude cocoon, threads of varying twist ready to be woven 115 and entirely ungummed which in a word 120 may be directly and immediately utilized for any use desired.

I claim—

1. The process of obtaining thread from 125 silk worm cocoons which comprises treating such cocoons in a bath containing an alkaline ungumming agent, and thereafter winding thread in its undried condition from the treated cocoons.

2. The process of obtaining thread from silk worm cocoons, which comprises treating such cocoons in a bath containing an alkaline ungumming agent and another substance capable of regulating the activity of said ungumming agent, and thereafter winding thread in its undried condition from the treated cocoons.

3. The process of obtaining thread from 10 silk worm cocoons which comprises treating such cocoons in a bath containing an ungumming agent, exposing the treated cocoons to a bath for removing the degumming agent, and thereafter winding thread in its undried 15 condition from the cocoons.

4. The process of obtaining threads from silk worm cocoons which comprises ungumming such cocoons in the cold, and thereafter winding thread from the cocoons thus 20 treated.

5. The process of obtaining thread from silk worm cocoons which comprises ungumming such cocoons in a cold alkaline bath, and thereafter winding thread from the 25 cocoons thus treated.

6. The process of obtaining thread from silk worm cocoons which comprises ungumming such cocoons in a cold alkaline bath, treating the cocoons to remove excess alkalinity therefrom, and winding thread from 30 the cocoons thus treated.

7. The process of obtaining thread from silk worm cocoons which comprises treating

such cocoons in a bath containing an alkaline ungumming agent until the gum is substantially all dissolved, and winding thread from the treated cocoons while they are still wet.

8. The process of obtaining thread from silk worm cocoons which comprises ungumming such cocoons in a bath containing an ungumming agent, treating said cocoons in a second bath to neutralize the ungumming agent, and winding thread from the treated 40 cocoons while they are still wet.

9. The process of obtaining thread from silk worm cocoons which comprises ungumming such cocoons in an ungumming bath and winding thread from the treated 45 cocoons while still wet.

10. The process of obtaining thread from silk worm cocoons which comprises ungumming such cocoons in an ungumming bath and winding thread from the treated 50 cocoons while still wet, the thread being exposed to the drying effect of the air in its travel from the cocoons to the winding mechanism so that it arrives at said mechanism substantially dry.

In testimony whereof I have signed this 55 specification in the presence of two subscribing witnesses.

BERNARD LOEWE.
